UNITED STATES PATENT OFFICE.

HOWARD R. BURK, OF BROOKLYN, NEW YORK.

COLORING KEROSENE-OIL.

SPECIFICATION forming part of Letters Patent No. 284,811, dated September 11, 1883.

Application filed January 2, 1883. (No specimen.)

To all whom it may concern:

Be it known that I, HOWARD R. BURK, of Brooklyn, in the county of Kings and State of New York, have invented certain new and useful Improvements in Coloring Kerosene-Oil, of which the following is a full, clear, and exact description.

The consumers of kerosene-oil desire that oil shall have a color pleasing to the eye, a blue or bluish color being the favorite. Kerosene-oil having this color is more salable than the ordinary oil.

The object of my invention is to impart to kerosene-oil a blue or bluish color in such a manner that the quality of the oil will not be impaired and the color will be retained and will not settle. Coloring-matter will not combine with kerosene-oil, nor dissolve in the same, on account of the peculiar qualities of kerosene, and if finely-divided or powdered coloring-matter is mixed with kerosene-oil it is only suspended mechanically, and will settle after a certain time, and the kerosene will lose its artificial color and resume its natural color.

25 Besides, the mixture of finely-divided coloring-matter impairs the quality of the kerosene-oil.

In order to avoid the above objections and to give the kerosene a permanent color, I color some solid or fluid substance very intensely, 30 which will dissolve in or thoroughly mix with the kerosene-oil. For instance, any fat, grease, oil, &c., that will readily dissolve in or mix with kerosene, and will not impair the quality of the same, is colored very intensely, and is then dissolved in or mixed with the kerosene, and imparts its color to the same in such a manner that the color will be permanent and the quality of the kerosene will not be impaired. For example, salts of copper or any 40 other analogous salts are dissolved in some oil that will readily mix with kerosene—for in-

stance olive-oil—and then the intensely-colored olive-oil is mixed with the kerosene. With one quart of olive or other oil, colored as described, I can color from two to three hundred 45 quarts of kerosene-oil. The color is not given to the kerosene for the purpose of giving it the color of a better quality of oil, as all qualities of kerosene-oil can be colored in this manner, but only for appearance, as most kerosene is burned in glass lamps, and thus can be seen, and for that reason it is desired to give the kerosene as pleasing a color as possible.

I do not limit myself to the coloring of kerosene-oil in the manner described above, but 50 can color any mineral oil by the above-described method.

I am aware that broadly it is not new to color naphtha by introducing therein a coloring substance unaccompanied by a vehicle or 55 agent conducive to the intimate union of the same with the naphtha.

Having thus fully described my invention, I claim as new and desire to secure by Letters Patent—

65 1. The method herein described of coloring kerosene, which consists in coloring a substance soluble in or capable of being thoroughly mixed with kerosene, and then dissolving or mixing the said substance or vehicle in 70 the kerosene, as and for the purpose set forth.

2. The described vehicle for coloring kerosene, which consists of a substance soluble in or capable of being thoroughly mixed with the kerosene, and of a coloring material dissolved 75 in said substance, as and for the purpose set forth.

HOWARD R. BURK.
